WALTER M. PETERS INVENTOR.

BY

Emil Tidmarsh ATTORNEY

UNITED STATES PATENT OFFICE.

WALTER M. PETERS, OF LINCOLN, NEBRASKA.

METHOD OF DRILLING A HOLE AND RELEASING A PILE ANCHOR.

Application filed December 29, 1922. Serial No. 609,635.

To all whom it may concern:

Be it known that I, WALTER M. PETERS, a citizen of the United States, residing at Lincoln, in the county of Lancaster and 5 State of Nebraska, have invented certain new and useful Improvements in Methods of Drilling a Hole and Releasing a Pile Anchor, of which the following is a specification.

10 My invention relates to piles and anchors of the type which are so constructed that a jet of water under pressure immediately beneath the lower end of the pile or anchor cuts out and tears away the soil, permitting 15 the weight of the pile to carry it down into the hole as fast as the hole is cut.

In prior devices of this kind two difficulties are frequently encountered, one relating to the waste of materials and the 20 other to the utter failure of the former methods under certain conditions.

In the former methods the pipe for carrying the stream of water is either embedded in the concrete pile itself or is carried at 25 the side of the pile and in such intimate relation therewith that there is no possibility of removing the pipe after the pile has been sunk. The great quantity of pipe which each pile carries is thus lost and 30 adds very materially to the cost of the operation. Then too, it is necessary whenever the pile is to be forced through refractory layers in the soil that the lower end of the pile be protected by means of a cap of boiler plate or other extremely hard steel. Because of the high cost of such steel and 35 because the caps must be made in comparatively small quantities, there is considerable waste from this source, as the caps are not recoverable after the pile has been 40 sunk.

It has also been found that when the pile in its descent encounters certain layers of soil, as for example layers of gravel, the 45 ordinary method of opening a passage for the pile by means of a jet of water fail because the gravel refuses to be dislodged. One of the usual methods of overcoming this difficulty is to raise the pile to a certain 50 height and then to let it drop. Unless the layer of gravel is too thick, the impact or several such impacts will force the pile through the layer. If on the other hand the layer of gravel is too thick or too firm, the 55 repeated impacts will batter first the boiler plate cap and then the pile itself, so that

it is no unusual thing to find a pile in which the lower half has been crushed into bits on its way through a layer of gravel.

In brief, the objects of my invention are 60 to provide a structure which includes a protector for the lower end of the pile and in which the protector as well as all of the pipes are easily recovered after the pile has been set, the protector being specially de- 65 signed to facilitate the passage of the pile through refractory soils.

The pile herein referred to may serve as a support for a superstructure and I do not desire to relinquish any of my rights 70 to the method or the structure when so used, but the immediate purpose of the pile is to make it serve as an anchor for a dike, break-water, or other obstruction. Other similar and analogous uses will probably be de- 75 veloped during the use of my invention, and I wish it understood that I lay claim to the structure and method regardless of the uses to which they are put.

Referring now to the drawings forming 80 part of this application, and in which like reference numerals refer to like parts in the description,

Figure 1 is a side elevation of my pipe frame for supporting the pile, and shows 85 one of the two halves of the frame as it appears before assembling.

Figure 2 is another side elevation of the same pipe frame as viewed from the side adjacent the side shown in Figure 1, and 90 shows the edges of both halves of the frame in their assembled relation.

Figure 3 is a top plan view of the pipe frame with a concrete pile in place therein.

Figure 4 is an edge view of one of the 95 latching plates and its connection with the frame.

Figure 5 is a face view of the parts shown in Figure 4.

Figures 6 and 7 are two views of the de- 100 vice which I use in connection with my pipe frame to protect the point or nose of the pile and to cut through refractory layers of soil in advance of the pile.

In carrying out my invention, I employ 105 two like frames of the kind shown in Figure 1. Each of these frames has an inside width which is slightly greater than the width of the pile which is to be sunk. The side edges of the frames are built up of sections 110 of pipe, the sections being placed end to end and connected by means of cross

— couplings 11. The number and length of the pipe sections 10 depends on the length of the pile and the depth to which it is desired to sink the pile, but more particularly on 5 the character of the soil through which the pile is to be driven. Soils like gravel or rock must be forced, and it is obvious that a much more rigid frame is required when such conditions are encountered than when 10 forcing the pile through clay.

Pipe sections 12 of suitable length, and secured at their ends in the cross couplings 11, connect the pipe sections 10 in parallel relation and serve also as braces and as conduits for the water which digs the hole in advance of the pile. The uppermost pipe length 12 is provided with a T-joint or coupling 13 for the reception of a hose 14 which is connected with a source of water 15 under pressure. At the lower end of each frame are two downwardly extending converging pipe lengths 15 connected by a Y-shaped coupling 16, the coupling 16 having connected thereto at its lower end a 20 nozzle 17.

Two frames as above described and as shown in Figure 1, are locked together in position on opposite sides of the pile to be sunk. The locking device is here briefly described. On each of the cross couplings 11 I secure a shouldered collar 18, and to the collar 18 I pivot a strap 19. The straps have apertures 20 at their free ends, the apertures being in alignment when the frame 30 is assembled. Pins 21 are provided for holding the straps together, each pin passing through the apertures of a pair of straps. The upper ends of the pins are connected to a cable 22 or other similar device for releasing the pins from the apertures 35 after the pile has been sunk. In the form shown in the drawings, the cable 22 is connected directly to the lowermost pin 21 but indirectly through yokes 23 with the other pins, each yoke being longer than the yoke immediately beneath and shorter than the yoke above. The effect of this construction is of course to cause the pins to withdraw in succession beginning with the 40 lowest pin. I may however vary this arrangement by reversing the lengths of the yokes so that the top pin will withdraw first, or if desirable I may dispense with the yokes entirely and withdraw the pins 45 all at the same time. It will be readily understood that when tension is applied to the upper end of the cable, as by means of a steam driven winding drum, the pins 21 will be withdrawn from the apertures 50 to release the connections between the halves 55 of the frame.

The pins 21 are wedge shaped to facilitate their withdrawal from the apertures. The shearing action of the straps results in 60 a more or less clamping effect on the pins

so that when tension is applied to the upper end of the cable, there is a tendency for the inner ends of the straps to be lifted and to thus clamp the pins more tightly. To avoid this difficulty I secure the straps to the collars in such a manner that the straps can not assume a position in which their outer ends are above the horizontal. This can of course be done in a number of different ways, one of which I have shown in detail in Figures 4 and 5. The collar 18 is provided with a pin 24 which is adapted to slide in the slot 25 of the strap to limit the pivotal movement of the strap.

When it is desired to sink a pile in clay or similar soil, the frame is assembled about the pile in the manner above described and is then lifted by means of a derrick or similar means to the position where it is to be sunk. Water under pressure is then forced 80 through the hose connections 14. The two streams of water, one on each side of the pile, pass down to the bottom of the frame where they are delivered as powerful jets through the nozzles 17 immediately underneath the nose of the pile. These jets of water tear away the clay and allow the pile to sink of its own weight, the water and clay being carried to the top along the sides 85 of the pile. When the pile has reached the desired depth the water action is temporarily stopped and the cables 22 are drawn up a sufficient distance to release all of the pins 21. The lower ends of the frame tend to spread away from and out of contact 90 with the pile when the connections are released, but in the event that the frame still adheres to the pile it is only necessary to lift the pile with the frame a few feet and then to drop them to release the frame from the 95 pile. The two halves of the frame can then be withdrawn from the hole by any suitable means, as for example a winding drum and cable. During the lifting of the frame the water under pressure is again forced through 100 the frame, as the force of the stream combined with the lubricating action of the water greatly facilitates the lifting of the frame. Apertures 26 in the pipes 15 are 105 designed especially for the purpose of supplying additional jets of water to assist in the lifting operation, but the jets of water coming from the apertures 26 also serve a useful purpose in cutting away certain kinds 110 of soil when sinking the pile.

When layers of gravel, rock, or other refractory materials are encountered it is necessary to supplement the water action, as the action of the water alone will not scour out a passage for the pile. The usual practice 115 is to provide the nose of the pile with a cap of boiler plate and then to repeatedly lift and to drop the pile until it has forced its way through the refractory layer. This practice has been found to be very costly,

both because the expensive cap is sunk beyond recovery with the pile and because of the number of piles ruined entirely or partially in the hammering process. I over-
 5 come this difficulty by securing to each half of the frame a cutting element 27. The cutting element 27 is susceptible of numerous variations, depending on the character of the material composing the layer through
 10 which it is desired to cut. It may have a single cutting edge or it may be folded over to present a double cutting edge as shown. The cutting edge may be straight or serrated or it may be a single, large tooth. The
 15 material from which it is made must be exceedingly hard and tough, such as armor plate or boiler plate.

The action with the cutter will be briefly explained. In gravel, the double, smooth-
 20 edge cutting plate is perhaps the best. The falling of the pile will cause the cutter elements and a portion of the pile to be embedded in the gravel. At the same time, powerful streams of water are passing out through the
 25 nozzles 17 and the apertures 26. The jets of water are more effective because they must travel in confined paths between the cutting plates and thus set in motion and clear out the gravel which is wedged between the
 30 plates. The eddying of the gravel laden stream of water about the bottom of the frame and the pile scours out a large cavity. The process of lifting and dropping the pile and its frame is repeated as many times as
 35 is necessary to force the pile through the refractory layer, after which the water action alone will carry the pile down lower. It should be here repeated that while the impact cutters and the water jets are both
 40 working, their interaction will make each more effective than when working independently.

In the case of rock layers, the operation is much the same as with gravel, but it may be desirable to slightly alter the form of the cutters. In gravel the cutters function very largely to segregate portions of the material where the water action is most effective, but in the case of rock layers it is necessary to
 45 first crush and break the layer, and the cutting tool should be selected largely with reference to the hardness of the layer through which it is desired to cut. After the rock has been crushed by the impact, the action of the water jets between the cutter plates will carry out the bits of rock in
 50 much the same manner as with gravel.

Having thus described my invention in a full, clear, and precise description, such as will enable others skilled in the art to which it pertains to make and to use the same, what I believe to be new and desire to secure by Letters Patent of the United States is:—

65 1. A structure for clearing a path in ad-

vance of a sinking pile, said structure including pipes which are adapted to be positioned at the lateral corners of the pile, said pipes being arranged in pairs, the pipes in each pair having connections for the flow 70 of water from one to the other of the pipes, each pair of pipes terminating in a nozzle at its lower end, both of said nozzles being positioned beneath the nose of the pile when the structure is in position, each pair of 75 pipes also being adapted to be connected with a source of water under pressure and means for releasably connecting the pairs of pipes to each other.

2. A structure for supporting a pile and for sinking a hole immediately in advance of the pile, said structure including means for ejecting jets of water under pressure beneath the nose of the pile, and cutting blades for penetrating the soil, said cutting 85 blades being so positioned that the jets of water will be confined in narrow channels between the cutting blades to dislodge and to remove the soil between the cutting blades.

3. Means for releasably securing a fluid transporting structure tightly against the outer surface of a pile, the fluid transporting structure consisting of two like parts which are adapted to bear against opposite sides 90 of the pile and having substantially the same width as the pile, links secured to each of said parts at their lateral edges, said links of the two parts being arranged in pairs and being so positioned that a link of one 95 of the parts will overlap the corresponding link of the other part, registering apertures in the links of each pair of links, and a releasable pin which is adapted to pass through the registering apertures to lock 100 said pair of links together.

4. A pair of fluid transporting structures which are adapted to be secured to bear against opposite lateral surfaces of a pile, each of said fluid transporting structures 110 having substantially the same width as that of the pile, a plurality of links pivotally secured to each of said structures at their lateral edges, the links of said two structures being in pairs and so arranged that the free 115 ends of the links of each pair will overlap, registering apertures in the overlapping portions of each pair of said links, a pin which is adapted to pass through the registering apertures to lock the links of each 120 pair of links together, and means for withdrawing said pin.

5. In combination with a pile and means for conveying a fluid under pressure to the lower end thereof, a nozzle for receiving the 125 fluid and for discharging it directly under the nose of the pile, and cutter blades positioned adjacent said nozzle and in substantially parallel relation to each other, said cutter blades being adapted to hack their 130

way into the soil when the pile is dropped and to thereby break up the soil, whereupon the fluid emerging from said nozzle will transport the loosened soil in the narrow channel between said cutter blades and thence upwardly along the sides of the pile.

6. A nozzle which is adapted to discharge a stream of fluid under pressure underneath the nose of a sinking pile, a pair of cutter blades secured in substantially parallel relation to each other and on opposite sides of said nozzle, and releasable means for securing said nozzle and cutter blades to the lower extremity of a pile, the arrangement being such that after the pile has been sunk to the desired depth, the securing means may be released and the nozzle and the cutter blades may be withdrawn and recovered.

7. A fluid conduit having a nozzle at one of its ends and means at the other of its ends for connecting it with a source of fluid under

pressure, means for releasably securing said fluid conduit to a pile with the nozzle directed to discharge the fluid underneath the nose of the pile, and plate like cutting blades secured to said fluid conduit, there being a cutting blade on each of two opposite sides of said nozzle with the cutting blades projecting beyond the extremity of the nozzle, the arrangement being such that the dropping of the pile will cause said cutting blades to initially loosen the soil and the stream of fluid discharged from the nozzle between the cutting blades will further loosen the soil and will transport the soil through narrow channels between the cutting blades and thence upward along the outer side of the pile.

In testimony whereof I affix my signature.

WALTER M. PETERS.
